Stephen W. Sullivan
By Percy H. Moore,
Attorney.

UNITED STATES PATENT OFFICE.

STEPHEN WARD SULLIVAN, OF INDIANAPOLIS, INDIANA.

OVERALLS.

Application filed October 24, 1921. Serial No. 510,045.

To all whom it may concern:

Be it known that STEPHEN WARD SULLIVAN, a citizen of the United States of America, residing at Indianapolis, in the county 5 of Marion and State of Indiana, has invented certain new and useful Improvements in Overalls, of which the following is a specification.

My invention relates to overalls and more 10 particularly to the apron or bib type of overalls.

The main object of my invention is to provide a pair of overalls with an apron or bib section which when folded inside the overalls, permits of the overalls being conveniently used as pants overalls.

Other and further objects and advantages of the invention will be in part obvious and in part described as the specification is proceeded with.

In the accompanying drawings forming part of this specification:

Figure 1 is a front elevation of the invention showing the bib or apron extended;

25 Figure 2 is a rear perspective view of the same;

Figure 3 is a perspective view of the invention showing the bib or apron folded inside of the pants;

30 Figure 4 is a section on the line 4—4 of Figure 1; and

Figure 5 is a detail of the bib or apron showing how the same is constructed and its parts connected together.

35 Referring more particularly to the drawings wherein like reference numerals refer to corresponding parts throughout the several views, 5 denotes a pair of overalls having the usual waist band or belt portion 6, rear

40 pockets 7 and side or front pockets 8. The waist band is also provided with the usual front and rear suspender buttons 14 and 15 respectively.

45 Secured at its lower edge to the waist band 6 is a bib or apron 9 comprising two similar sections 10 and 11. These sections are permanently attached to the inside of the waist band, one on each side of the fly 12 of the pants as by stitching 13. The section 10 50 of the bib or apron is provided with buttons 16 on its inner edge and the section 11 has correspondingly located button holes 17, for the obvious purpose of detachably connecting the adjacent edges of the sections, together to

form the apron or bib. It will also be noted 55 from an inspection of Figure 3 that the sections 10 and 11 are provided with button holes 18 and 19 respectively adjacent the lower ends of their outer edges for receiving the suspender buttons 16 at the front of the 60 waist band or belt portion 6. This button and button hole connection between the waist band and the bib or apron assists the rows of stitching 13, by reason of the fact that part of the upward pull or tension on the 65 bib 9 is transferred from the line of stitching to the said connection and then transferred to the waist band 6. This connection further assists in keeping the waist band 6 in upright condition at the front of the body. 70 If the stitching 13 rips or breaks, the apron 9 will still be connected to the waist band 6.

75 By separating the bib 9 into sections 10 and 11 and detachably connecting them together the wearer has immediate, comfortable and easy access to certain parts of the body when the fly 12 is being used and the bib 9 as such is in its inoperative position as in Fig. 3. It will be noted in Fig. 1 that the point of separation between the sections 10 80 and 11 is in alignment with the fly 12, so that, when the bib 9 is in its inoperative position (Fig. 3) the point of separation between the said sections will be directly behind the fly 12. A still further object of said 85 sectional bib 9 is to allow the sections to be separately placed down and within the lower portion of the garment when on the wearer's body thereby preventing a crowding of the material and uncomfortable action at the 90 waist line when the garment is on the body and the wearer desires to use the garment only as a pair of trousers.

95 When the apron or bib is in use, that is when the garment is used as a bib overall, the 100 suspenders 21 are connected by the wearer in the usual way to the suspender buttons, both front and rear on the waist band 16, and the loops 22 secured to the front straps 23 of the suspenders are connected to the suspender buttons 24 on the bib or apron. It will be noted from Figs. 1 and 2 that the front straps 23 are positioned behind the bib 9 and covered thereby, from the waist line up to the loops 22. It will thus be seen that the 105 suspenders support both the body of the overalls and the bib or apron. If the wearer desires to dispense with the bib or apron,

it is merely necessary to disconnect or unbutton the sections 10 and 11 of the bib or apron 9 along their adjacent edges, and also unbutton the button holes 18 and 19 on the 5 lower edge of the sections 10 and 11 of the bib from the suspender buttons 16 on the waist band. The sections 10 and 11 can then be conveniently folded downwardly inside the body of the overalls, on opposite sides of 10 the fly 12. It will of course, be understood that the loops 22 must be disconnected from the buttons 24 before the bib can be folded to Figure 3 position. When in folded position it will be noted the apron is suspended from 15 the row of stitching 13. It will also be noted that by reason of the bib 9 being connected to the lower edge of the waist-band the tendency of the bib 9 to show above the top edge of the trousers when the bib as such is in its 20 inoperative position is reduced to a minimum and the thickness of the top edge of the trouser portion is not increased and unnecessary bulging at this point is avoided.

Having thus described my invention:

What I claim as my invention is:

A garment of the class described comprising a trouser portion having a waist-band, an apron composed of two sections detachably connected together, stitches connecting the lower edges of said sections to the inner lower edge of said waist-band, detachable means connecting said sections to said waist-band above the inner lower edges thereof, and suspenders having the rear end thereof connected to the trouser portion at the rear and the front ends thereof connected to said waist-band at the front and means intermediate the front and rear ends thereof for connecting the said apron thereto.

In testimony whereof I affix my signature in presence of two witnesses.

STEPHEN WARD SULLIVAN.
